UNITED STATES PATENT OFFICE.

HENRY BARNES, OF CLEVELAND, OHIO.

TOOTHBRAHSH.

Application filed February 12, 1926. Serial No. 87,789.

One of the chief causes of diseases of which my brush is intended to be held during use. the mouth is improper use of the tooth brush. Experience has shown that the popular methods employed in the brushing 5 of teeth have produced injury to the gingivæ, in that the manner in which the brush is grasped by the hand and the pressure which is exerted under vigorous muscular tension, together with the scrubbing and brushing to and fro, up and down, circularly and rotary, have a tendency and actually do force the gingivæ from their normal cervical constriction, and thereby induce gingivitis. Experience has also shown that 15 food lodged underneath the lacerated and inflamed gums, on being forced between the teeth and gums has caused "spongy" gums, which later permit the development of pockets and ultimately allow the establishment 20 of pyorrhea.

Considerable thought and ingenuity have been expended in an endeavor to effect a satisfactory cleansing of the mouth, but the remedies have been directed toward the 25 adaptation of existing brushes, the bristles of which are only adapted to act on the surface of the teeth at right angles to the axes thereof. Moreover, an attempt to force the bristles into the interdental space at right 30 angles to the long axes of the teeth, tends to cause the gums to be flattened on their interdental apices. As a result, the gums will lose their interproximal apical form.

A principal object of the present invention 35 is to provide a brush by means of which proper interdental brushing may be obtained. In this connection I contemplate the provision of a brush which when properly used, as will be hereinafter set forth, will 40 conserve the dental tissues, will cause the gums to form about the teeth in the proper direction, and will effect a thorough cleansing action of the interdental spaces. Moreover a brush made in accordance with my 45 invention and when used as hereinafter set forth will produce a gentle stimulating message of the gum tissues without irritation or observable tooth abrasion.

In the drawings, Fig. 1 is a side elevation 50 of a tooth brush embodying my invention; Fig. 2 is a plan view of the brush; Figs. 3 and 4 are sections taken through the brush on planes indicated by the correspondingly numbered lines in Fig. 1; Figs. 5 and 6 are 55 perspective views illustrating the manner in

I have illustrated my brush as having a single row of bristles which are carried in a brush head, or back 10 which may be 60 formed of any suitable material in one piece with the handle 11. The width of the head is sufficient only for providing the necessary mechanical strength to support a single row of bristles whereby a comparatively small 65 head is obtained.

The arrangement of the tufts of bristles and their relation to each other as well as their shape are important characteristics of the present invention. For example, I 70 have illustrated five tufts in a single row, as indicated at 15, 16, 17, 18 and 19 respectively. One similarity of the tufts is the fact that the edge of each is beveled to form a knife-edge across the center. The tufts 16 75 and 18, however, are different from the remaining tufts in that they are relatively shorter and that the beveled edges extend in a direction parallel to the longitudinal direction of the handle, while the remaining 80 tufts, namely 15, 17 and 19 have the beveled edges extending in a direction transversely to the longitudinal direction of the handle. Thus I provide a brush wherein the edges are arranged alternately at sub- 85 stantially right angles to each other, and wherein tufts of long and short bristles are arranged alternately to each other. The beveled edges of the long tufts, however, extend parallel to each other while the bevel- 90 edges of the short tufts are substantially in alignment with each other.

To use a brush made in accordance with my invention, a pivotal hold is made with the tip of the thumb and forefinger close 95 to the bristles. This manner of holding the brush will permit the compensating action of the brush, hand and wrist to follow the contour of the dental arch. Accordingly the brush hold must be flexible rather than 100 rigid and the brush should be held between the thumb and finger tips rather than in the palm of the hand. The position illustrated in Fig. 5 is that employed by a right handed person who is about to clean the upper right hand side of the mouth, while the position illustrated in Fig. 6 is that used 105 by a right handed person who is about to clean the upper left hand side of the mouth. In cleaning the upper portion of the 110

mouth, the side of the brush is laid on the cervical margin of the upper gum and inclined to an angle of about 30 degrees with the gum. Then with a slight arm and shoulder motion, the brush is brought gently downward and inward so that the edges of the bristles 15, 17 and 19 pass along the gums and then inward between the teeth, while the bristles 16 and 18 pass down along the gums, then over the outer surface of the teeth. During this downward motion the brush is "jiggled" so as to work the bristles more thoroughly into the interdental spaces. For brushing the lower gums and teeth, the position of the brush is reversed and the operation is repeated. During the brushing operation the bristles do not leave the surface but slide down and slide up on the upper jaw, and slide up and slide down on the lower jaw, whereby a gentle massaging effect is obtained without injury to the tissue.

To facilitate the pivotal holding of the brush, I provide a concave surface 20 along one side of the handle and another concave surface 21 along the opposite side of the handle. These concave surfaces provide grooves which function as guides into which the tips of the fingers naturally fall when the brush is to be used, and are helpful in that they enable the user to guide the brush in the proper manner during the brushing operation. Moreover the grooves tend to obviate the tendency for one to grasp the

brush in the palm of the hand and thereby 35 to employ improper technic for the brushing operation. The width of the handle, particularly at the midportion, is considerably greater than the width of the head, while the concave construction is employed in a 40 transverse as well as in a longitudinal direction.

I have found that a tooth brush made in accordance with the present invention and used as heretofore described has beneficial 45 effects not only in modifying injuries which may be due to improper brushing or other causes, but also for insuring the maintenance of healthy gum tissue in a surprising manner.

Having thus described my invention, I claim:

1. A tooth brush having a series of tufts of bristles arranged in a row, each tuft having the end thereof beveled, and the beveled edges being arranged alternately at substantially right angles to each other.

2. A tooth brush having a series of spaced single tufts of bristles arranged in a row, some of the tufts being comparatively long, 60 and others being comparatively short, the long and short tufts being arranged alternately, the short tufts being beveled in the form of a knife-edge, and the edges being substantially in alignment with each other.

In testimony whereof, I hereunto affix my signature.

HENRY BARNES.
